UNITED STATES PATENT OFFICE.

WILLIAM J. LUSE, OF NEW YORK, N. Y.

FIRE-ALARM SIGNALING SYSTEM.

Application filed June 8, 1920. Serial No. 387,287.

To all whom it may concern:

Be it known that I, WILLIAM J. LUSE, a citizen of the United States, residing at New York city, borough of Manhattan, county and State of New York, have invented a certain new and useful Fire-Alarm Signaling System, of which the following is a specification.

This invention is a fire alarm signaling system and is more particularly a system embodying improvements on my prior invention described and claimed in Patent No. 1,344,701, granted June 29, 1920.

The object of both inventions, speaking generally, is the notification of a central station, e. g., a telephone office, that a fire has broken out in a particular locality, wherein the signaling apparatus is installed. In the prior construction, the apparatus was constituted to operate in a purely mechanical way, whereas in the present invention, the apparatus is electrically controlled through the employment of novel electrical means.

The underlying principle of my invention is to associate with a telephone instrument, phonographic means capable of being brought into operation by an appreciable rise in temperature, such as would be produced by fire, either in the immediate vicinity of the apparatus, or within any part of the building, apartment or office, with which the apparatus is operatively connected. My invention further embodies means normally maintaining the telephone instrument inoperative, but rendering the same operative in the event of fire, so that when the phonographic means is brought into operation automatically by the starting of a fire, the telephone instrument is simultaneously rendered effective to transmit the alarm to a central office.

The object of the present invention is to effectively control the operation of the apparatus by electrical means, thereby facilitating the installation of the same and extending the zone of the protection. This being possible through the employment of electricity of a much greater degree than is possible through the employment of purely mechanical means.

Features of the invention, other than those adverted to, will be apparent from the hereinafter detailed description taken in conjunction with the accompanying drawings.

The accompanying drawings illustrate one practical embodiment of the invention, but the construction therein shown is to be understood as illustrative, only, and not as defining the limits of the invention.

Figure 1 is a more or less diagrammatic view of the invention; and,

Figure 2 is a perspective view of one of the details of construction of the apparatus.

Referring to the drawings, 1 is a box or housing adapted to be positioned in any suitable place, and may, if desired, be secured to the wall of the building interiorly thereof. The box 1 may be of wood, metal or any other material desired and simply forms a housing for the mechanism or apparatus enclosed therein.

Positioned within the box 1 is a phonographic instrument 2, here shown as mounted on brackets 3. The instrument 2 is of conventional form and embodies, among other details, the usual turn table 4 for supporting the record. The record preferably embodies the following sentence, or some other appropriate alarm repeated over and over for the full scope of the record; "Central notify fire headquarters, 1600 Rhinelander, that there is a fire at 312 W. 20th St., fourth floor rear."

A tone arm 5 carries a sound box 6, which cooperates with the record when the instrument is operating for the purpose of delivering sounds to an outlet 7 with which the tone arm 5 is connected.

Also mounted interiorly of the box as on a shelf 8 is a telephone instrument 9, also of conventional form provided with the usual hook 10 adapted to support the receiver 11. The telephone is connected through suitable electrical connections either with the telephone central office as usual, or with any suitable central office, such as the office of the police or fire department central or the like. It will be noted that in Figure 1 the telephone instrument is so positioned in the box that the mouth of the transmitter 12 is directly adjacent and in alignment with the outlet 7 of the tone arm, so that if the phonograph is put into operation and the hook 10 of the telephone instrument raised, the sounds produced by the phonograph will be transmitted through the telephone instrument to the central office.

As stated, the receiver hook 10 of the telephone instrument is normally depressed by the weight of the receiver 11, but is adapted,

by the present invention, to be elevated in the event of fire by means of a flexible chain or cable 13, which is secured to the hook 10, by a small hook 13', passes upwardly and over a directional pulley 14 positioned exteriorly of the box and thence downwardly into the box and has secured to its free end a weight 15. When the weight is imposed upon the hook 10, it overbalances the receiver 11, lifts the hook 10 and renders the telephone instrument operative. The weight 15 is normally, however, maintained in a raised position by means of an electrically operated trip adapted to be released in the event of fire. This trip is shown as embodying a hinge 16, one leaf 17 of which is secured to a bracket 18 on the box 1 and the other leaf 19 of which is bifurcated or slotted at 20 to allow of the passage of the flexible connection 13 therethrough. The free end of the bifurcated leaf 19 is adapted to cooperate with the armature 21 of an electromagnet 22. The armature 21 is pivoted to a fixed part 23 and a spring 24 normally impels the armature 21 into engagement with the end of the bifurcated leaf 19, causing the end of said leaf to enter a notch 25 in the armature 21 as shown. The parts are so constituted, however, that if the magnet 22 is energized, the armature will be drawn toward the same and away from the leaf 19 with the result that the latter will become disengaged and is free to gravitate into the dotted line position in Figure 2.

35 The flexible connection 13 has associated therewith a ball or knob 26 firmly fixed thereon and of such size as to normally rest upon the bifurcated leaf 19 of the hinge and by such engagement support the weight 15, so 40 that it is not imposed upon the hook 10 of the telephone instrument. However, if the magnet 22 is energized and releases the bifurcated leaf of the hinge as specified, the weight 15 will be imposed upon the hook 10 45 and thereby bring the telephone into operative condition.

As the operation of the apparatus of this invention depends upon the conjoint operation of both the telephone and phonographic instruments, the weight 15 is so organized as to render both of these instruments simultaneously operative. This may be accomplished in several ways, but as shown, the phonograph is controlled through a flexible connection 27 which is secured to the weight 15 at one end, passes over directional pulleys 28 and is secured at its other end to the brake 29 of the phonograph. This brake is so constituted that it normally brakes the phonograph, but is adapted, when tension is placed upon the flexible connection 27, to release the phonograph for operation and effect the immediate starting of the same.

It will thus appear that the releasing of 55 the weight by the magnet 22 as described

will instantly place both flexible connections 27 and 13 under tension and simultaneously start the phonograph and condition the telephone instrument to receive and transmit the message conveyed thereto by the phonograph.

Associated with the electromagnet 22 is an electrical circuit 30 fed from any suitable source of electrical energy, here shown as dry batteries 31, although such energy may be supplied from street current or by any suitable means. The circuit 30 may lead through various parts of the building or to any other enclosure which it is desired to protect against fire, and at suitable intervals or suitable points in said circuit thermostatic regulators 32 are included, preferably in multiple as shown. In the event of fire, at any point within the zone of protection of the system, the thermostatic regulator in the vicinity will serve to complete the circuit 30, energize the magnet 22 and cause the giving of the alarm. I may also associate with the circuit 30, a shunt circuit 33, in which is included a bell or buzzer 34 positioned at any desired point. This shunt circuit is, however, normally broken at a knife switch 35 positioned directly below the weight 15. When the weight drops, it will automatically close the knife switch 35 and effect the ringing of the bell 34, so that the alarm will not only be given at the central office, but also at the point where the bell 34 is located. It will thus appear that the present invention embodies not only the modification of a central office, but also the giving of a local alarm.

In practically carrying out the present invention, the phonograph instrument 2 may be of any one of many conventional types. In the form shown it is of the type embodying a spring motor which may be wound up and in condition to operate the instrument as soon as the brake is released. I may, however, operate the phonograph instrument from an electric motor in which event, the flexible connection 27 instead of leading to the brake 29 of the instrument may simply lead to an open switch in the motor circuit. As motor operated phonographic instruments are common in the art, I have not considered it necessary to show the same in the construction, as the arrangement described will be well understood by those skilled in the art. It is also within the scope of the present invention to employ a motor operated phonographic instrument and include the motor in the circuit 30, thereby entirely dispensing with the flexible cable 27. When this apparatus is employed, current may be supplied by other means than the batteries 31, preferably by a street current.

From the foregoing description, it will appear that in the event of fire an alarm will

be given to a central office through the telephone instrument and at the same time, a local alarm will be given by the bell 34 and this alarm will be substantially continuous. 6 In practice, I preferably associate with the phonograph any one of several well known forms of repeater, so that the record will be played over and over until the spring motor runs down. It is not desirable, however, 10 that the telephone instrument should be operating indefinitely and, accordingly, I include in the flexible connection 13 a fusible link 36, so that if the fire commences to burn about the box 1, the fusible link 36 will melt, allow the hook 10 of the telephone to descend and break the telephone circuit. The box 1 is preferably made of metal so as to preclude the contents thereof against fire in the immediate vicinity. 20

While the present invention is particularly adapted for notification of fire, it may be also adapted for use as a burglar alarm by simply changing the record to embody appropriate phraseology and instead of employing thermostatic switches 32, the circuit 30 may be led through the building in a concealed manner and suitable windows, door or manually controlled switches associated therewith. In this event, the bell 34 may be employed or dispensed with as desired. 30

It will be noted that the present invention as described does not, in any way, form an encumbrance to the telephone instrument or necessitate a change in the construction therein. In fact, if the door provided in the box 1 is opened, connection 13 may be disengaged from the telephone hook and the telephone may be then removed from the box and employed in the usual manner to carry on a conversation. The outlet 7 of the tone arm is not attached to the mouth piece 12 of the transmitter, but simply positioned 40 immediately adjacent thereto. 45

Having thus fully described the invention, what I claim as new and desire to secure by Letters Patent is:

1. An apparatus of the class described embodying a phonograph, a telephone instrument positioned with the transmitter thereof adjacent the outlet of the tone arm of the phonograph, tension means associated with the telephone instrument and weighted 50 to lift the receiver hook of the telephone instrument when the weight is imposed upon the tension means, means for normally holding said weight in restraint, electrical means for releasing said weight, and means also associated with the weight and operable thereby to start the phonograph when the weight is released, in combination with a local circuit embodying a local alarm, and a controlling switch, said switch being positioned 55 in the path of the weight and adapted to be

actuated thereby when the weight is released to close the local circuit and cause the giving of the alarm.

2. An apparatus of the class described embodying a normally inoperative phonograph, a normally inoperative telephone instrument positioned with its transmitter in cooperative relation to the sound outlet of the tone arm of the phonograph, a weight operatively associated with both the phonograph and the telephone instrument and adapted, when released, to simultaneously render both the phonograph and telephone instrument operative, means for normally maintaining the weight in restraint, electrical means for releasing the weight, a normally open operating circuit, and a switch adapted to complete the circuit for the purpose of energizing the electrical means to effect the release of the weight, in combination with a local circuit embodying a local alarm, and a controlling switch, said switch being positioned in the path of the weight and adapted to be actuated thereby when the weight is released to close the local circuit and cause the giving of the alarm. 80

3. An apparatus of the class described embodying a normally inoperative phonograph, a normally inoperative telephone instrument positioned with its transmitter in cooperative relation to the sound outlet of the tone arm of the phonograph, a weight operatively associated with both the phonograph and the telephone instrument and adapted, when released, to simultaneously render both the phonograph and telephone instrument operative, means for normally maintaining the weight in restraint, electrical means for releasing the weight, a normally open operating circuit, and a switch adapted to be closed, for the purpose of energizing the electrical means to effect the release of the weight, in combination with a switch positioned below the weight and normally maintained in open position, a local alarm, and a circuit including the switch and local alarm, whereby the weight, will, when released, descend upon the switch and cause the closing thereof for the purpose of completing the circuit to the local alarm. 100 110

4. An apparatus of the class described embodying a normally inoperative phonograph, a normally inoperative telephone instrument positioned with its transmitter in cooperative relation to the sound outlet of the tone arm of the phonograph, a weight operatively associated with both the phonograph and the telephone instrument and adapted, when released, to simultaneously render both the phonograph and telephone instrument operative, means for normally maintaining the weight in restraint, electrical means for releasing the weight, a normally open operating circuit, and a switch adapted to be closed for the purpose of ener- 120 125 130

gizing the electrical means to effect the release of the weight, in combination with electrical means including an alarm, and means operable by the released weight for effecting the operation of such alarm.

5. An apparatus of the class described embodying a phonograph instrument, a mechanical connection controlling the operation of said instrument, a telephone instrument positioned with its transmitter in cooperative relation to the sound outlet of the tone arm of the phonograph instrument, a mechanical connection, associated with the telephone instrument for controlling its operativeness, a common weight associated with both mechanical connections, means for normally keeping the load of the weight off of both mechanical connections, and electrical means for imposing the load of the weight upon the flexible connections for the purpose of simultaneously rendering the phonograph and telephone instrument operative in combination with a normally open switch positioned within the path of the released weight and normally free from engagement therewith, a local alarm, and a circuit including the switch and local alarm whereby the weight, when released, will descend upon the switch and effect the closing thereof to complete the circuit to the local alarm.

6. An apparatus of the class described embodying a phonograph instrument, a mechanical connection controlling the operation of said instrument, a telephone instrument positioned with its transmitter in cooperative relation to the sound outlet of the tone arm of the phonograph instrument, a mechanical connection, associated with the telephone instrument for controlling its operativeness, a common weight associated with both mechanical connections, means for normally keeping the load of the weight off of both mechanical connections, and electrically operated means for imposing the load of the weight upon the flexible connections for the purpose of simultaneously rendering the phonograph and telephone instrument operative, in combination with a normally open electrical circuit embodying an alarm, and means included in said circuit and adapted to be engaged by the released weight to complete said circuit for the purpose of effecting operation of the alarm.

7. An apparatus of the class described embodying a phonograph instrument, a mechanical connection controlling the operation of said instrument, a telephone instrument positioned with its transmitter in cooperative relation to the sound outlet of the tone arm of the phonograph instrument, a mechanical connection, associated with the telephone instrument for controlling its operativeness, a common weight associated with both mechanical connections, means for normally keeping the load of the weight off of

both mechanical connections, and automatically operable electrical means for imposing the load of the weight upon said connections for the purpose of simultaneously rendering the phonograph and telephone instruments operative, in combination with means operable by the released weight for effecting a local alarm.

8. An apparatus of the class described embodying a phonograph, a telephone instrument, the transmitter of which is positioned in cooperative relation to the sound outlet of the phonograph tone arm, means for controlling the operation of the telephone instrument, means for controlling the operation of the phonograph instrument, a common weight cooperating with the controlled means of both the telephone instrument and the phonograph, for simultaneously effecting the operation of both, when the weight is released, means for normally maintaining the weight in restraint, and automatically operable in the event of fire, electrical means, automatically operable in the event of fire, for releasing the weight, in combination with means operable by the released weight for effecting a local alarm.

9. An apparatus of the class described embodying a phonograph, a normally set brake associated therewith, a telephone instrument positioned with its transmitter in cooperative relation to the sound outlet of the phonograph tone arm, a common weight, a cable secured to the weight and to the receiver hook of the telephone instrument, a second cable secured to the weight and to the brake of the phonograph, an electromagnet provided with an armature having a shoulder, a pivoted plate associated with one of said cables and normally resting on the shoulder of said armature for the purpose of carrying the load of the weight, so that the load of such weight is not operatively imposed upon said cables, and an electric circuit associated with said electromagnet and embodying thermostatic switches adapted to be automatically closed in the event of fire, for the purpose of releasing the pivoted plate and imposing the load thereof upon the cables to simultaneously render the phonograph and telephone instrument operative.

10. An apparatus of the class described embodying a phonograph, a normally set brake associated therewith, a telephone instrument positioned with its transmitter in cooperative relation to the sound outlet of the phonograph tone arm, a common weight, a cable secured to the weight and to the receiver hook of the telephone instrument, a second cable secured to the weight and to the brake of the phonograph, an electromagnet provided with an armature having a shoulder, a pivoted plate associated with one of said cables and normally resting on the

shoulder of said armature for the purpose of carrying the load of the weight, so that the load of such weight is not operatively imposed upon said cables, and an electric circuit associated with said electromagnet and embodying thermostatic switches adapted to be automatically closed in the event of fire, for the purpose of releasing the pivoted plate and imposing the load thereof upon the cables to simultaneously render the phonograph and telephone instrument operative, in combination with an electric circuit including an alarm and a switch positioned to be engaged by the released weight to complete the alarm circuit.

11. Apparatus of the class described embodying a phonograph, a telephone instru-

ment positioned with the transmitter thereof adjacent the outlet of the tone arm of the phonograph, tension means associated with the telephone instrument and weighted to lift the receiver hook of the telephone instrument when the weight is imposed upon the tension means, means for normally holding said weight in restraint, means for releasing the weight, means also associated with the weight and operable thereby to start the phonograph when the weight is released, and repeating mechanism associated with the phonograph whereby the record of said phonograph may be repeated.

In testimony whereof, I have signed my name to this specification.

WILLIAM J. LUSE.
